UNITED STATES PATENT OFFICE.

WILLIAM E. SCHIEBLE, OF MIAMISBURG, OHIO.

RAILWAY SIGNAL SYSTEM.

SPECIFICATION forming part of Letters Patent No. 786,604, dated April 4, 1905.

Application filed May 16, 1904. Serial No. 208,170.

To all whom it may concern:

Be it known that I, WILLIAM E. SCHIEBLE, a citizen of the United States, residing at Miamisburg, in the county of Montgomery and State of Ohio, have invented certain new and useful Improvements in Railway Signal Systems, of which the following is a specification, reference being had therein to the accompanying drawings.

This invention relates to railway signal systems, and more particularly to electric signaling systems, its object being to provide a simple and efficient block-signaling system adapted for use more particularly in connection with interurban electric-railway lines, although capable of other applications.

More specifically, the objects of my invention are, first, to provide a simple and efficient structure whereby a car or train upon entering a block at either end thereof will render operative a signal at each end of the block, said signals remaining operative until the car leaves the block, whereupon said signals become inoperative; second, to provide a signaling system employing a metallic circuit a portion of which is divided into two branches between which the signaling-lamps are located, the branch circuits being controlled by rotating switches or commutators which are in turn controlled by the movements of the car, so that said signaling-lamps are arranged in parallel or multiple arc between said branch circuit when the signals are operative, said signaling-lamps being arranged in series when inoperative and the current being then short-circuited, so as to extinguish the signal-lamps.

To these and other ends my invention consists in certain novel features, which I will now proceed to describe and will then particularly point out in the claims.

In the accompanying drawings, Figure 1 is a plan view in the nature of a diagram, illustrating the application of my invention to a single-track railroad having turnouts or passing sidings at intervals. Fig. 2 is a front elevation of so much of the system as relates to one complete block or section. Fig. 3 is a plan view of what is shown in Fig. 2. Fig. 4 is an enlarged front elevation of one of the rotary switches or commutators detached.

Fig. 5 is a longitudinal sectional view of the same, taken on the line *x x* of Fig. 4 and looking in the direction of the arrows; and Fig. 6 is a transverse sectional view taken on the line *y y* of Fig. 5 and looking in the direction of the arrows.

Referring first to Fig. 1, A indicates the main line of a railway, having turnouts or passing tracks at B, C, D, and E. The space between two of these turnouts constitutes a block or section and is protected by a separate and independent signaling structure, one of which is shown in Figs. 2 and 3. Each of these signaling structures comprises a signaling-station at each end, indicated in the present instance by the reference-letters F and G, these stations being located at the junction of the turnout with the main line and the signals being preferably located a sufficient distance from the actual point of connection to permit the motorman to observe their operation after the car has actuated them. Referring to Figs. 2 and 3, I have shown for convenience of illustration the signaling-lamps as located directly below the controlling-switches or commutators; but in practice the arrangement just described will be preferred. The station F comprises a suitable support 1, on which is mounted a commutator 2, its location being such, preferably by reason of its elevation, that it will not be readily accessible to the public, while at the same time it is adapted to be engaged and actuated in the manner hereinafter described by a suitable projecting member carried by the car. The form of construction which I prefer for this part is that shown in detail in Figs. 4, 5, and 6 of the drawings, in which said commutator has a body portion 3, of insulating material, and is mounted upon an axis 4, preferably of conducting material, which is fixed in the support 1 and upon which the commutator is free to rotate. The peripheral portion of this commutator is provided at intervals with metallic contact-pieces 5, separated by the intervening exposed portions 6 of the non-conducting body of the commutator, and the contact-strips 5 are electrically connected with the axis 4, preferably by means of a terminal plate 7, to which said strips are connected and which 100

is in contact with the axis 4 or its terminal head 5. In order to obtain a better contact, each strip 5 is preferably provided with a boss or enlargement 6, having a depression 7, which serves as a detent in the manner hereinafter described. The commutator 2 is provided with projecting fingers 8, one for each strip 5 and insulating-space 6, and these fingers are arranged in the path of the projection on the car, so as to be moved thereby when in contact with the same a distance equal to the space between two adjacent fingers 8.

On the support 1 are mounted two contact arms or brushes 12 and 13, provided with bosses 14 at their free ends adapted to engage the recesses 7. These brushes are so arranged relatively to the commutator that when one of them bears upon a contact-strip 5 the other one bears upon an intermediate non-conducting surface 6. The signaling-lamp 15, preferably an incandescent lamp, is connected with the brushes 12 and 13 by a wire 16.

The signaling-station G is constructed in a manner similar to the signaling-station F, and the contact-strips of the commutators at the two stations are connected with a common source of electricity, preferably by connecting their pivotal axes 4 by wires 17 with a source of electricity 18, which may be a battery or the trolley or supply wire of the railway in the case of an electric railway. The brush 12 of the commutator at station F is connected with the brush 13 of the commutator at station G by a line 19, and the brush 12 at station G is connected with the brush 13 at station F by a line 20.

When the parts are in the position shown in Figs. 2 and 3, the signal-lamps are extinguished, the circuit being from the source 18 through line 17 to the axis 4 of the commutator at station F and thence through plate 7 and contact-strip 5 at said station to the brush 12. It will be observed that from this point the circuit between the stations is divided into two branches 19 and 20, and the current follows the branch 19 directly to the brush 13 at station G, which is in contact with one of the strips 5 of the commutator at station G, following thence through plate 7 and axis 4 at said station G and through line 17 back to the source 18. The other branch of the circuit extends from the brush 12 at station F through line 16 and lamp 15 to brush 13 at station F and thence through line 20 to brush 12 at station G and from this latter brush through line 16 and lamp 15 to brush 13 at station G. It will be seen that with the parts in the position shown the lamps are in series, so as to offer an increased resistance to the current along this branch, the current being, in fact, short-circuited between the brush 12 at F and brush 13 at G along the line 19, so that the signal-lamps do not burn. This is the position of the parts when the block is free, 65 no car having entered it from either end.

Upon the entrance of a car from either end—as, for instance, in the case of a car starting from siding B toward siding C, as indicated by the arrow in Fig. 1—the car will, by means of the projecting arm with which it is furnished, engage the lowermost finger 8 of the commutator at station F and turn said commutator one space. The brush 12 at station F will then rest upon an insulating-space, while the brush 13 at station F will rest upon one of the contact-strips 5. In assuming this position the part 14 of the brush will engage the recess 7 of the strip, arrest the movement of the commutator at the proper point and hold it in position, thus acting as a detent and preventing overthrow or excessive movement of the commutator. As soon as this change has taken place at F the circuit is as follows: The current from the source 18 passes through line 17 to the axis 4, plate 7, and strip 5 at station F, with which strip the brush 13 is in contact. At brush 13 at station F the current divides, one part of it passing through line 16 and lamp 15 at station F to brush 12 at station F and thence through line 19 to brush 13 at station G. The other part of the current passes from brush 13 at station F through line 20 to brush 12 at station G and from this latter brush through line 16 and lamp 15 to brush 13 at station G, where the current is again united. From brush 13 at station G the current passes through plate 7 and axis 4 at station G to line 17 and back to source 18. In this position of the parts it will be seen that the signal-lamps are in parallel or multiple arc between the brushes 12 of the two stations, and they therefore burn, remaining operative as long as the car remains on the block between stations F and G. When said car reaches station G, its projecting arm will engage the lowermost finger of the commutator at said station and will so turn said commutator as to again short-circuit the current, this time between brush 12 at station G and brush 13 at station F, throwing the signal-lamps into series and extinguishing them. The same result occurs when a car proceeding from siding C to siding B enters the block at station G—that is to say, the partial rotation of the commutator at G in the reverse direction to the movement last referred to will light the signal-lamps whether the parts be in the position shown in Fig. 2 or in the position which they will have assumed after the passage of a car through the block from B to C. In fact, a car entering the block from either end will light the lamps and will extinguish them when it leaves the block after having traversed the same, so that the presence of a car upon the block will always be indicated by a lighted lamp at each end thereof.

Obviously the details hereinbefore described may be modified without departing from the principle of my invention. For instance, if it is desired to so operate the sys-

tem that any impairment of its functions will give a danger-signal this can be done without any change of structure by merely employing the lighted lamps as safety-signals, the unlighted lamps being used to indicate "danger," in which case any accident to the lamps or circuits which would extinguish the lamps would signal "danger." To accomplish this, it is only necessary to turn either one of the commutators from the position shown in Fig. 2 to a position in which the lamps are lighted, whereupon a car entering the block will extinguish the lamps to show "danger" and will light the lamps upon leaving the block to indicate "safety." It will also be seen that the signal-lamps instead of being connected directly to the brushes at each station may be connected anywhere between the two branch circuits connecting the two stations, and it is obvious that any desired number of signal-lamps may be employed located at any desired points, and such arrangement may be found advisable, since it would indicate to the train crew of a car or train traversing a block the unauthorized entrance upon the block at either end of another car or train by the extinguishing of the lamps throughout the section. It will be further understood that other visible or audible signals may be substituted for the lamps. Various other modifications will readily suggest themselves, and I do not wish to be understood as limiting myself to the precise details of construction hereinbefore described and shown in the accompanying drawings.

It will be understood that the projection from the car is, as usual, under the control of the train crew, so that it may at any time be withdrawn in such a way as to not engage and operate the signals, thus permitting the running of a plurality of cars or trains as a single train or double-header, the first car controlling the signals at the entrance of a block or section and the last car controlling the signals at the end of a block or section.

Having thus fully described my invention, what I claim as new, and desire to secure by Letters Patent, is—

1. In an electric signaling system for railroads, signaling-stations located at the opposite ends of a section of track, each station comprising a commutator actuated by the passing car and having alternating contact and insulating surfaces, and two brushes arranged

to alternately contact with the contact-surfaces of the commutator, a circuit comprising a source of electricity and connecting said stations, one portion of said circuit connecting the contact-surfaces of the two commutators, and the other portion of said circuit being divided into two branches connecting the brushes of the two stations in pairs, one at each station, and signal-lamps arranged in parallel or multiple arc between the said branches of said circuit, substantially as described. 55

2. In an electric signaling system for railroads, signaling-stations located at the opposite ends of a section of track, each station comprising a commutator or rotating switch 70 actuated by the passing car, said commutator having alternating contact and insulating surfaces, two brushes arranged to alternately contact with the contact-surfaces of the commutator, and a circuit connecting said brushes 75 and provided with a signal-lamp, and a circuit connecting said two stations, one portion of said circuit comprising a source of electricity connected with the contact-surfaces of both commutators, the other portion of said circuit 80 being divided into two branches, each branch connecting a brush at one station with a brush at the other station, substantially as described.

3. In an electric signaling system for railroads, signaling-stations located at the opposite ends of a section of track, each station comprising a commutator or rotating switch 85 actuated by the passing car in the direction of its motion, said commutator having alternating contact and insulating surfaces, two 90 brushes arranged to alternately contact with the contact-surfaces of the commutator, and a circuit connecting said brushes and provided with a signal-lamp, and a circuit connecting said two stations, one portion of said circuit 95 comprising a source of electricity connected with the contact-surfaces of both commutators, the other portion of said circuit being divided into two branches, each branch connecting a brush at one station with a brush at 100 the other station, substantially as described.

In testimony whereof I affix my signature in presence of two witnesses.

WILLIAM E. SCHIEBLE.
